UNITED STATES PATENT OFFICE.

FRANK W. PEEK, JR., OF PITTSFIELD, MASSACHUSETTS, ASSIGNOR TO GENERAL ELECTRIC COMPANY, A CORPORATION OF NEW YORK.

PROTECTIVE DEVICE.

Application filed May 20, 1918, Serial No. 235,450. Renewed July 19, 1922. Serial No. 576,150.

To all whom it may concern:

Be it known that I, FRANK W. PEEK, Jr., a citizen of the United States, residing at Pittsfield, county of Berkshire, State of Massachusetts, have invented certain new and useful Improvements in Protective Devices, of which the following is a specification.

My invention relates to protective devices and more particularly to devices for the protection of electrical conductors from conditions of lightning disturbances, transients and other over-voltage phenomena.

The object of my invention is to provide a device which is operative to relieve a conductor from excessive voltage conditions caused by transients, surges and similar phenomena and more specifically to provide a spark gap device for use in outdoor service, which will discharge at very nearly its dry arc-over voltage setting independent of the weather conditions with substantially no time delay between the application of arc-over voltage and the discharge across the device and which is, in general, an improvement on similar devices heretofore known in the art.

It is well known, as described in U. S. Letters Patent No. 1,232,467, granted to me, that a protective or spark gap device which comprises two cooperating electrodes having their proximal surfaces in the form of surfaces of revolution, such as two spheres, and separated by a certain distance relative to the radius of the spheres, forms a spark gap having a substantially uniform dielectric field. When arc-over voltage occurs across such a gap, there is substantially no time delay between the occurrence of arc-over voltage and the rupture of the dielectric or the discharge across the gap, that is, there is no formation or brush discharge of corona prior to the discharge of the gap to introduce a time delay. A sphere gap so proportioned is therefore very fast and serves to quickly relieve from the conductor to be protected, all excessive voltage conditions and particularly surges of steep wave front. An arrester comprising a gap is, however, not always at maximum efficiency when used for outdoor service due to the fact that the spacing must be varied because of weather conditions, for example, rain, snow, and ice collecting upon the electrodes

serve to lower the voltage at which an arc-over will occur as the wet arc-over voltage of the gap is lower than the dry arc-over voltage.

According to my invention, I provide a protective or sphere gap device of the type described, which is operative in a substantially uniform dielectric field and hence with substantially no time delay, provided with means for protecting the spark gap from conditions of the weather whereby the device is operative out of doors at its dry arc-over voltage setting practically independent of the weather conditions, and whereby the dielectric field is maintained uniform so that the time delay is unaffected. I maintain the arc-over voltage of the spark gap device constant and substantially independent of the weather, by protecting each electrode with a metallic hood or shielding means and for preventing such protecting means from distorting the dielectric field and hence increasing the time delay, I prefer to provide the shielding member for each electrode of a configuration or of a contour to follow a substantially equipotential surface for the electrodes, that is, all points on the shielding means is at substantially equal potential. The field of the main gap thus remains practically unchanged when the shields are introduced.

The novel features which I believe to be characteristic of my invention will be definitely indicated in the claims appended hereto while the features of construction and method of operation will be understood by reference to the accompanying drawings in which:

Figure 1 is a view, partly in section, of an arrester or spark gap device embodying the features of my invention; Fig. 2 shows a modified form of my invention; Fig. 3 is a sectional view of a further modified form of my invention, and Fig. 4 is a top elevation of the device shown in Fig. 3.

In Fig. 1 my arrester or spark gap device comprises cooperating electrodes 1 and 2 having their proximal surfaces in the form of surfaces of revolution. In the preferred form, the proximal surfaces are spherical and separated by a distance having such a relation to the radius of the spheres, as to provide a spark gap having a substantially uniform dielectric field. A spark gap of

2
this construction has practically no time lag, that is, there is practically no time delay between the occurrence of arc-over voltage and the discharge of the gap. Furthermore, a gap of this construction has an impulse ratio of substantially unity. By the term impulse ratio, I mean the ratio of the impulse arc-over voltage to the continuously applied arc-over voltage which means, in other words, that with an impulse ratio of unity the gap will discharge at its arc-over voltage setting independent of whether the impressed voltage is continuously applied or whether it occurs at successive or intermittent impulses such as transients or surges of steep wave front.

In order to render the discharge of my spark device independent of weather conditions, and hence enable the device to be applicable to outdoor use, I provide a means for maintaining the voltage of the gap at which an arc-over occurs always controlled by the dry arc-over voltage setting. For accomplishing this function I provide a shielding means for protecting the spark gap device from the weather, and according to the drawings I provide a specific form of shielding means which possesses certain advantages over other types used for this purpose.

In order to keep the impulse ratio of the sphere gap substantially unity and also to prevent an increase in the time lag of the gap, a shielding means for the gap which does not distort the dielectric field possesses material advantages. I obtain these advantages by providing a shielding means which has a contour, or is shaped to follow the points of equal potential in the dielectric field. In Fig. 1, I have shown a shield 3 of thin metal inclosing sphere electrode 1 of a contour following an equipotential surface surrounding the electrode and which I designate as an equipotential shield. This shield is insulated from the electrode 1 by an insulating member 4 which also serves to support the equipotential shield 3 in position. Similarly an equipotential shield 5 incloses the cooperating electrode 2 and is supported by the insulating member 6 and is thus insulated from the electrode. I have thus provided a shielding means which enables the spark gap device comprising the electrodes 1 and 2 to be protected from weather conditions and which is controlled from its dry arc-over voltage setting. At the same time the shielding means does not distort the dielectric field and hence does not impair the time delay of the device. As shown in Fig. 2, I may utilize a horn gap to quickly extinguish the arc, and for this purpose horn members 7 and 8 are provided suitably opposed to the shield members 3 and 5. For purpose of illustration I have shown an electrolytic cell 9 in series with

the spark gap, such a device serving to extinguish the arc which follows the discharge across the gap as is well known in the art.

In Figs. 3 and 4 I have shown a modified spark gap device embodying my invention in which the cooperating electrodes comprise a conducting ring or annular member 10 and a rod or cylindrical member 11. In protecting these electrodes I provide a shielding means consisting of an annular or ring-shaped shield member 12 inclosing electrode 10 and a cooperating shield member 13 inclosing electrode 11, said shields having a contour to follow an equipotential surrounding the respective electrodes. In the illustration shown electrode 10 is connected to the conductor to be protected and electrode 11 is connected to ground through, for instance, an electrolytic cell 9 for the purpose above set forth.

85

What I claim as new and desire to secure by Letters Patent of the United States, is,—

1. In a protective device, the combination with cooperating electrodes spaced apart to form a spark gap, of shielding means for said electrodes having a contour corresponding substantially to an equipotential surface.

90

2. In a protective device, the combination with cooperating electrodes spaced apart to form a spark gap, of a shield partially enclosing each electrode but insulated therefrom, said shields having a contour such that all points thereof are at substantially the same potential.

95

3. In a protective device, the combination with cooperating electrodes spaced apart to form a spark gap, of means for shielding said electrodes comprising a conducting shell having a contour corresponding substantially to an equi-potential surface.

100

4. In a protective device, the combination with cooperating electrodes spaced apart to form a spark gap, of shielding means for protecting each of said electrodes from the weather having a form corresponding substantially to an equipotential surface whereby the characteristics of said gap are unchanged.

105

5. In a protective device, the combination with two cooperating electrodes having their proximal surfaces spherical and spaced apart to form a spark gap, of shields surrounding each of said electrodes, but insulated from the same, said shields having a contour corresponding substantially to an equipotential surface.

110

6. The combination with an electrode member, of a shield partially inclosing said electrode member insulated therefrom and of a contour conforming substantially to an equipotential surface, and a second electrode member cooperating with said first mentioned electrode member to form a spark gap.

115

7. In a protective device, the combination

120

125

130

with two cooperating electrodes spaced apart to form a spark gap and shaped to provide a substantially uniform dielectric field, of means having substantially the shape of an equipotential surface for shielding said electrodes without distorting said electric field.

8. In a protective device, a protective gap

formed with an electrode and a metallic shielding member therefor comprising a sheet lying substantially along an equi-potential surface.

In witness whereof I have hereunto set my hand this 14th day of May, 1918.

FRANK W. PEEK, JR.
